[57] CLAIM

The ornamental design for a urine leg bag, as shown and described.

DESCRIPTION

FIG. 1 is a front elevational view of a urine leg bag, showing our new design;

FIG. 2 is a rear elevational view thereof;

FIG. 3 is a side elevational view thereof, the opposite side being identical;

FIG. 4 is a top plan view thereof; and

FIG. 5 is a bottom plan view thereof.

FIG.4

FIG.1

FIG.3

FIG.2
